UNITED STATES PATENT OFFICE.

PER A. PETERSON, OF NEW YORK, N. Y.

FLYING-MACHINE.

1,273,267.

Specification of Letters Patent. Patented July 23, 1918.

Application filed May 27, 1916, Serial No. 100,182. Renewed June 5, 1918. Serial No. 238,395.

To all whom it may concern:

Be it known that I, PER A. PETERSON, a citizen of the United States, and a resident of New York city, in the county of New York and State of New York, have invented certain new and useful Improvements in Flying-Machines, of which the following is a specification.

This invention relates to improvements in flying machines wherein oscillating wings are used to elevate and buoy the device and supplemental wings or blades are provided to drive the machine forward with the back stroke of the wings.

One object of the invention is to provide a construction in which a lifting action is obtained in both the forward and reverse movement of the wings.

Another object is to provide means whereby the supplemental wings may be folded when the machine is to be landed or when it is hovering over a given spot.

A further object is to provide means for taking up the inertia of the wings during the reversing movement.

The various further objects and advantages will more fully appear from the detailed description and the features of novelty will be particularly pointed out in the claims.

In the drawings illustrating one embodiment of the invention,

Figure 1 is a perspective view of the machine.

Fig. 2 is a vertical sectional view of the same.

Fig. 3 is a plan view partly in section.

Fig. 4 is a diagrammatic view of the wing movement.

Fig. 5 is a similar view showing the elevating motions of the wings.

The improved flying machine has a body provided with a seat 11 for the aviator and seats 12 for passengers with lockers beneath. The body may be mounted on wheels 13 to move the machine along the ground and provided with floats 14 at suitable points to support the device on the water, while a propeller 15 is also provided to drive the machine when afloat. Beneath the seat 11 is located a motor 16, which may be thrown in gear with the shaft of the propeller 15 under these conditions, but which ordinarily drives the wings hereafter de-

scribed. The motor is controlled by the lever 16 beside the aviator's seat.

Back of the seat 11 is a standard 17 supporting a platform 18 at the front of which is hinged a deflector 19 operated by means of a lever 20 and a rod connector 21, and which is swung up or down to cause the machine to rise or descend when desired.

At the front and rear of the platform are buffer springs 22 and running around the sides are the guide rods 23, beneath which play the arms 24 of the wings 25.

Nearly all of the flying insects are provided with two sets of wings, one set on each side. The uppermost of these wings is to elevate the body while the under set is to move the insect forward, the former vibrating on a plane slightly departing from the horizontal, and with great rapidity, while the under wing is moving on a plane almost vertical, and by which the insect is able to move with great rapidity.

This fact is very noticeable in the common house fly, whose wings are hardly flexible, but are movable at the point of attachment to the body, so that their planes may be altered to produce the results above described.

The construction, arrangement and operation of the wings of the machine as shown in the drawings, is very similar to those of the insect as above described. The wings 25 move on horizontal lines, but are convex with the outer end 26 and also the rear edge (Fig. 2) raised so that as the wing moves forward and cuts into the air, the volume of the latter on the under side is compressed by the rounded under surface of the wing, and floats the machine. These wings and arms are as lightly constructed as possible and may be of metal or bamboo and fabric while hinged to their front edge and on the under side of the wings are the secondary wings or blades 27 adapted to open with the back stroke of the wings, but to close with the forward stroke. At the end of each stroke, the arms 24 strike the buffer springs 22 and thus the inertia of the moving wings is taken up without jar. Furthermore, the energy stored up in the springs at the end of the stroke is given up at the beginning of the following stroke facilitating the reverse movement of the wings without loss of power.

The wings are operated by the motor 16 through the lever 28 pivoted at the back of the standard 17 and by means of the links 29 connected with the hinge 30 at the top of the lever. The lower end of the lever is operated by crank arms 31 through the links 32.

The inner ends of the blades 27 terminate in stems 33 with crank arms 34 at their ends, 10 the latter being connected by means of links and springs 35 with the standard so that with the forward movement of the wing and arm the spring and link tighten on the arm 34 and draw the blade tightly against the 15 wing, allowing it to offer no obstruction to the air.

When it is desired or necessary to retard the forward movement of the machine, the 20 blades are held tightly against the under sides of the wings by means of a foot lever 36 which is connected by means of the cords 37 with arms 38 on the stems 33, so that they will not exert any pressure on the air as the 25 wings move. They may also be rendered inoperative when descending.

The rudder 39 is pivoted on rearwardly extending arms 40 of the standard and is controlled by a lever 41 at the left of the 30 aviator, and connections 42 which are attached at both sides of the lever and the rudder, so as the lever is moved down the rudder is deflected in one direction and an upward move throws it in the reverse way.

Diagram Fig. 4 shows the throw of the 35 wings, which is about a quarter of a circle and in Fig. 5, the dotted lines show the movements of the convex wing and its influence on the elevation of the machine while vibrating.

40 At convenient points brackets 43 may be located for the mounting of guns which may be arranged to fire in any direction.

It is obvious that for convenience of illustration, the wings 25 are of much smaller 45 dimensions than when actually used as compared with the other parts of the machine. The parts may be otherwise arranged and modified to lighten the construction and provide for a practical device without departing from the essential features above described or from the scope of the appended 50 claims.

Having thus described my invention, I 55 claim as new and desire to secure by Letters Patent:

1. In a flying machine, the combination with the frame thereof, of horizontal oscillating wings of upwardly concave contour whereby horizontal movement of the wings 60 in either direction exerts force to raise the machine, and means for driving the wings.

2. In a flying machine, the combination with the frame thereof, of horizontal oscillating wings, secondary wings connected

with the first mentioned wings adapted to 65 open at the rearward movement of the main wings and to close at the forward movement of the main wings, manually controlled means for folding the secondary wings to the main wings, and means for driving the 70 wings.

3. In a flying machine, the combination with the frame thereof, of horizontal oscillating wings of upwardly concave contour whereby horizontal movement of the wings 75 in either direction exerts force to raise the machine, secondary wings connected with the first mentioned wings adapted to open at the rearward movement of the main wings and to close at the forward movement of 80 the main wings, manually controlled means for holding the secondary wings to the main wings, and means for driving the wings.

4. In a flying machine, lifting wings, propelling blades movably connected with the 85 lifting wings, and manually controlled means for folding the propelling blades to the lifting wings when it is desired to land.

5. In a flying machine, oscillating lifting wings having an upwardly curved edge at 90 the forward and rear edge thereof to secure lifting action both at the forward and rearward movement of the wings.

6. In a flying machine, an oscillating lifting wing, a propelling blade movably mounted 95 thereon, means for automatically and positively opening the blade on the rearward movement of the wings to form a pocket for the propulsion of the machine, said blade folding back during the forward 100 movement of the wing, and means for driving the wings.

7. In a flying machine, oscillating lifting wings, propelling blades movably mounted on the lifting wings, said lifting wings having surfaces to secure a lifting action both at the forward and rear strokes of the wings and the propelling blades having propelling action at the rearward movement of the 110 wings.

8. In a flying machine, the combination with a water tight body having floats and wheels, of a standard in the body and having a platform at its top, oscillating wings pivoted on the platform, blades hinged to 115 the front edges of the wings and adapted to open with the back stroke of the wings, buffer springs for the wings, a motor, a lever operated by the motor, and links connecting the lever with the wings.

9. In a flying machine, the combination with a buoyant body having wheels, of a standard, a motor at the base of the standard, a propeller and shaft operated by the motor, a platform at the top of the standard, 125 spring buffers, arms pivoted on the platform and having dished wings at their outer ends, a lever pivoted on the standard, means con-

nected with the motor for operating the lever, links connecting the lever with the arms of the wings, blades hinged beneath the wings, means for throwing the blades out of operation, a rudder, and a deflector. Signed at New York city, in the county of New York, and State of New York, this 24th day of May, A. D. 1916.
